HANS WEICHSEL, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

STARTING APPARATUS FOR INTERNAL-COMBUSTION ENGINES.

1,353,876.

Specification of Letters Patent. Patented Sept. 28, 1920.

Application filed May 23, 1919. Serial No. 299,318.

To all whom it may concern:

Be it known that I, HANS WEICHSEL, a citizen of Germany, residing at the city of St. Louis, State of Missouri, United States of America, have invented a certain new and useful Starting Apparatus for Internal-Combustion Engines, of which the following is such a full, clear, and exact description as will enable any one skilled in the art to which it appertains to make and use the same, reference being had to the accompanying drawings, forming part of this specification.

Some internal combustion engines, and particularly air cooled engines, will sometimes revolve backward, due to self ignition. This is particularly likely to occur when the engine is being stopped. When such an engine is connected to a cranking motor by means of an overrunning-clutch and reduction gearing, there is danger, upon its reversal, of the motor being driven at a speed which will wreck the machine although the power developed by the internal combustion engine under the circumstances named is not very great.

It is the object of my invention to overcome the above difficulty and in its broadest aspect the invention comprises means for providing a load resisting rotation of the engine in a direction opposed to its normal direction of rotation, and in the specific form herein illustrated I so organize the motor circuits that should the engine reverse backward the motor will act as a generator and thus prevent development of dangerously high speed.

In the accompanying drawing which illustrates one embodiment of my invention the armature 2 of the engine starting motor is connected to the engine shaft 6 by means of an overrunning clutch 5 diagrammatically illustrated. The motor is provided with a shunt field winding 4 and a series winding 3 and its circuits and connections with the starting battery 8 are controlled by the two-pole switch 7. In the position shown, which may be termed the "off" position, the switch 7 closes the armature circuit of the motor through the series winding 3 and the resistance 9 and connects the shunt winding 4 in series with the battery 8. In the starting position of the switch,

the switch arms contact with points 10 and 11 and connect the battery to the armature 55 in series with the field winding 3.

It will be understood that the switch 7 is provided with any suitable means such as a spring 12, whereby when released by the operator it will assume the position 60 shown in the drawing and will occupy this position at all times except when intentionally brought to the starting position for the purpose of cranking engine.

Back-firing of the engine usually takes 65 place when the operator cuts off the ignition to stop the engine. Backward rotation of the engine produces the same relation between the clutch elements 5 as produced when the motor is cranking the engine and the engine will therefore drive the motor, but since at such time the switch 7 closes the armature circuit over the series winding and the resistance 9 and also connects the battery to the shunt winding 4 the 70 rotation of the motor in the backward direction will cause it to act as a generator thus constituting a brake preventing the comparatively small power developed by self-ignition from producing a speed high 75 enough to cause mechanical injury to the motor.

It will be understood that since in the connections shown the motor is capable of self-excitation due to the fact that the armature circuit is closed through the series winding the separately excited shunt winding may be omitted but that this winding being constantly excited serves to immediately cause the production of current in 80 the armature circuit. The shunt winding 4 may also be connected to the armature brushes instead of to the battery, if the advantages of separate excitation of this winding are deemed unnecessary. The resistance 85 9 serves to limit the output of the motor, operating as a generator, and its use for such purpose is well understood.

Having fully described my invention, what I claim as new and desire to secure by 100 Letters Patent of the United States is:

1. The combination with an internal combustion engine, a starting motor therefor, an overrunning clutch for connecting the motor to the engine, and means for short 105 circuiting the motor to cause it to act as a

generator when the engine operates under its own power in the direction opposed to its normal direction of rotation.

2. The combination with an internal combustion engine, of a series starting motor therefor, a battery, an overrunning clutch adapted to connect the motor to the engine when the motor operates to drive the engine, a switch for connecting the battery to the motor and means whereby said switch in its off position short-circuits the motor.

The combination with an internal

combustion engine, of a series starting motor therefor provided with a shunt winding, a battery, one-way clutch means adapted to connect the motor to the engine when the motor operates to drive the engine, a switch for connecting the battery to the motor, and means whereby said switch in its off position short-circuits the motor and connects the battery to the shunt winding.

In testimony whereof, I have hereunto set my hand and affixed my seal.

HANS WEICHSEL. [L.S.]
